(57) **CLAIM**

The ornamental design for an electrical generator adapter with indicator light, as shown and described.

DESCRIPTION

FIG. 1 is a top, right front perspective view of an electrical generator adapter with indicator light embodying our design; FIG. 2 is a bottom, left back perspective view of same electrical generator adapter with indicator light as in FIG. 1 embodying our design;

FIG. 3 is a front side elevational view thereof;

FIG. 4 is a back side elevational view thereof;

FIG. 5 is right side elevational view thereof;

FIG. 6 is a left side elevational view thereof;

FIG. 7 is a top plan view thereof; and,

FIG. 8 is a bottom plan view thereof.
